UNITED STATES PATENT OFFICE.

JESSE B. GARBER, OF SALEM, OHIO, ASSIGNOR TO THE DEMING COMPANY, OF SALEM,
OHIO, A CORPORATION OF OHIO.

PUMP.

949,423.

Specification of Letters Patent. Patented Feb. 15, 1910.

Application filed August 9, 1909. Serial No. 511,961.

To all whom it may concern:

Be it known that I, JESSE B. GARBER, a citizen of the United States, residing at Salem, in the county of Columbiana and State of Ohio, have invented certain new and useful Improvements in Pumps; and I do hereby declare the following to be a full, clear, and exact description of the invention, such as will enable others skilled in the art 10 to which it appertains to make and use the same.

My invention relates to pumps, and more particularly stated to that class of pumps which are designed, arranged and adapted 15 for pumping both air and water into a storage tank or reservoir, from whence the water may be distributed, under pressure throughout the pipes and connections of a water service system.

Among its objects my invention contemplates the production of pumps of the character stated, which are at once simple in construction, responsive in action, economical in point of power required, and of greater 20 general efficiency than those heretofore employed for similar purposes.

The present invention will be hereinafter particularly described and pointed out in the claims following.

In the accompanying drawings which form part of this application, and whereon corresponding reference characters indicate like parts in the several views: Figure 1 represents in side elevation my invention 30 with lower pumping cylinder attached, the latter broken away exposing the lower end of a piston rod, piston, and in side elevation the foot valve. Fig. 2 represents a longitudinal central section through a portion of the invention, on an enlarged scale. Fig. 3 35 is a transverse section taken on the line 3—3, Fig. 2, and Fig. 4 is also a transverse sectional view taken on the line 4—4, Fig. 2.

Reference being had to the drawings, it 40 will be apparent that the leading features of my present invention are contained within what may be termed a mixing cylinder, as distinguished from the pumping-cylinder located below, the latter being of any well 45 known construction and forming no part of this invention *per se*. It will be noted also that no particular means for reciprocating the piston rod are shown, for the reason that any well known reciprocating mechanism 50 may here be employed.

The mixing apparatus, which is preferably of cylindrical form, may or may not be provided with a brass or other lining, and is formed of upper and lower sections 1, 2 respectively, the adjacent ends whereof are 60 connected by a coupling 3 in screw threaded relation. To the opposite ends of said sections 1 and 2 are screwed end couplings 4 and 5, each suitably packed as at 6 and threaded interiorly at 7 to receive tubular 65 connections.

Extending longitudinally through center of the mixing apparatus aforesaid is a piston rod 8 adapted to be reciprocated in any approved manner and to control the action 70 of an ordinary pumping cylinder 9 below. To said piston-rod is secured a plunger mechanism comprising a cage 10 threaded upon said rod below the rod coupling 11, a tubular plunger 12 depending from said 75 cage and passing loosely through a central aperture 13 in the coupling 3 aforesaid, an annular follower 14 threaded upon the exterior surface of plunger tube 11 adjacent to its point of connection with cage 10, a 80 cup packing 15 securely held between the plunger follower 14 and the lower edge of cage 10 its free edge bearing upon the interior of the upper cylinder section 1 or the lining thereof, and finally a similar but 85 oppositely arranged cup packing 16 securely held between the upper end of cylinder section 2 and the coupling 3. It will be noted that the free edge or inner periphery of the last named packing is arranged to surround 90 and snugly engage the outer circumference of the plunger tube 12 and is beveled as shown to facilitate a self packing action under the upward pressure of a column of water within the cylindrical section 2. In a 95 similar manner the cup-packing 15 is circumferentially flexed outwardly or inwardly according to a preponderance of pressure in the mixing chamber 17 or the cylindrical section 1 above. At a point somewhat removed from its lower open end said plunger tube 12 is perforated as at 19 for purposes 100 that will later appear.

Entering at one side of the coupling 3 is an air inlet port 20 which may be tapped as 105 shown to receive a regulating cock (not shown). Intersecting this port 20 is a vertically arranged air passage 21 communicating with an enlarged seat 22 for a ball valve 23 and opening directly into the an- 110

nular mixing chamber 17 surrounding the plunger tube 12 beneath its follower 14, as shown by Fig. 2.

Screwed into the lower coupling 5 is the 5 tubular pumping cylinder 9 of any approved diameter, length and capacity, or as is frequently necessary in deep wells said cylinder may be more or less extended by the interposition of a tubular connection or pipe 10 (not shown), but in any event containing the usual pumping piston 24 secured to and moving with the piston rod 8, and also the usual foot valve 25 as shown by Fig. 1.

This being a description of my present 15 invention in one form of construction, it will be noted that various changes in the matter of materials employed, the form, arrangement and construction of parts may be made and substituted for those herein 20 shown and described without departing from the spirit of the invention, the operation, however, remaining substantially the same, and being as follows: An upstroke of the piston rod 8 from its lowermost position 25 as indicated by Figs. 1 and 2 of the drawings, in addition to elevating water by agency of a partially submerged pumping cylinder 9 in the usual manner, carries with it the cage 10, cup packing 15, follower 14 and tube 12, thus tending to produce a partial vacuum in the annular mixing chamber 17 beneath said follower. As the plunger mechanism ascends, air rushes into said chamber 17 via the air inlet port 20 and ball 30 valve 23, the ordinary pumping mechanism in the meantime inducing an upward flow of water into the cylinder section 2 and through plunger tube 12. Near the top of each stroke, as the port 19 passes above the cup 35 valve 16, water escapes from within tube 12 to the mixing chamber 17 until pressure is equal in both, whereupon with each down-stroke of the plunger mechanism said mixture of water and air from chamber 17 is 40 forced past the circumferentially yielding upper edge of packing 15 into the stream flowing through tube 12 and is thence delivered to its place of utilization, as for example, a storage and pressure reservoir.

45 Having thus described my invention, what I claim and desire to secure by Letters Patent is:

1. In an apparatus of the character described the combination with means for inducing a flow of water therethrough, of a 50 mixing chamber, an air inlet to said chamber,

ber, a reciprocating air pumping plunger, a tube depending from said plunger, and a port in said tube adapted to deliver water into the mixing chamber following each charge of air thereto, substantially as described.

2. In an apparatus of the character described the combination with means for inducing a flow of water therethrough, of a 55 mixing chamber, an air inlet to said chamber, a check valve guarding said inlet, a reciprocating piston rod, an air pumping plunger carried by said rod, a tube depending from said plunger, and a port in said tube adapted to deliver water into the mixing chamber following each charge of air thereto, substantially as described.

3. In an apparatus of the character described the combination with means for inducing a flow of water therethrough, of a 60 mixing chamber, an air inlet to said chamber, a reciprocating piston rod, an air pumping plunger carried by said rod, an open ended tube passing through said plunger, 65 and a port in the depending portion of said tube adapted to deliver water into the mixing chamber periodically, substantially as described.

4. In an apparatus of the character described the combination with means for inducing a flow of water therethrough, of a 70 mixing chamber, an air inlet to said chamber, a reciprocating piston rod, a cage carried by said rod, a plunger secured to said 75 cage, a tube depending from said plunger, and a port in said tube adapted to deliver water into the mixing chamber following each charge of air thereto, substantially as described.

5. In an apparatus of the character described the combination with a pump for inducing a flow of water therethrough, of a 80 mixing chamber, an air inlet to said chamber, a reciprocating air pumping plunger, 85 a tube depending from said plunger, and a port in said tube adapted to deliver water into the mixing chamber following each charge of air thereto, substantially as described.

100 In testimony whereof I affix my signature, in presence of two subscribing witnesses.

JESSE B. GARBER.
